No Drawing. Application May 6, 1941,
Serial No. 392,138

6 Claims. (Cl. 260—513)

1

This invention relates to a process for solubilizing hydrocarbons, and more particularly it relates to a process for solubilizing olefin hydrocarbons. More specifically, this invention relates to an efficient process for converting olefin hydrocarbons containing at least six and preferably more than eight carbon atoms to soluble aliphatic sulfonic acids having valuable properties as surface-active agents.

With the growing use of synthetic surface-active agents in the textile industry, it has become an increasingly important problem not only to develop more efficient reagents but to find new and cheaper sources of raw materials from which to produce them. Since aliphatic hydrocarbons of the type derived from petroleum are both cheap and abundant, they have been of particular interest as starting materials for obtaining suitable low cost textile chemicals. It has been proposed, for example, to oxidize certain petroleum fractions with air to produce long-chain acids for use in the manufacture of soap. In general, however, soaps of this type differ but little from soaps prepared by classical methods from fats and are subject to the same disadvantages as regards calcium sensitivity. Many of the disadvantages of soaps for use in the fields of textile assistants and finishing agents can be avoided by employing synthetic reagents such as long-chain alkyl sulfates or aliphatic sulfonic acids of appropriate molecular weight. The sulfonic acids are particularly valuable, not only because of their high efficiency as wetting agents and detergents, but because of their stability toward hydrolysis and efficiency in hard water. Accordingly, the discovery of a novel and practical synthesis of surface-active sulfonic acids from long-chain olefin hydrocarbons as provided by the process of this invention comprises an important contribution to the art of textile reagent manufacture.

According to this invention, monoolefin hydrocarbons containing at least six and preferably more than eight carbon atoms are converted to sulfonic acids having valuable properties as surface-active agents by reacting the monoolefin at elevated temperatures with free sulfur to produce a sulfurized olefin, hydrogenating the sulfurized olefin at elevated temperatures and pressures in the presence of a sulfactive hydrogenation catalyst to give a product consisting mainly of mono-thiol, and then oxidizing the hydrogenated sulfurized monoolefin with suitable chemical reagents.

The following general procedure is employed in converting long-chain olefins to sulfonic acids:

2

One mole of monoolefin is mixed with at least one, generally with at least two moles and preferably not more than 4 moles of powdered sulfur and heated to a temperature of about 150° C. for a period of 3 to 8 hours. The resulting mixture, which consists of a dark-brown somewhat viscous oil, is transferred without further treatment to a high pressure vessel and hydrogenated at 125° C. to 200° C. and a pressure of about 1500—2500 lbs. per square inch during a period of 3 to 8 hours. After cooling the autoclave, the product is removed and distilled to obtain the corresponding mono-thiol, which is converted to the desired sulfonic acid by oxidation under mild conditions with an appropriate reagent such as 70% nitric acid. The free sulfonic acid is neutralized with an alkali such as sodium hydroxide to obtain a surface-active product characterized by excellent wetting, detergent, and sudsing properties.

The following examples show in greater detail the practice of this invention in several of its modifications. The amounts of materials referred to are in parts by weight, unless otherwise specified.

Example I

Seventy parts of pentadecene-7 and 35 parts of powdered sulfur are charged into a reaction vessel equipped with a thermometer, agitator, a reflux condenser, and a gas inlet tube for blanketing the reaction mixture with an inert gas. The contents of the vessel are heated to about 160° C. After about one hour all the sulfur has dissolved, and the color of the reaction mixture has changed from yellow to brown. Heating at 160° C. is continued for an additional 6.0 to 6.5 hours to complete the reaction. The product is cooled and diluted with an equal volume of dry ether. On standing the ether solution deposits 5 parts of unreacted sulfur, which is separated by filtration. After clarifying the filtrate with activated carbon, evaporation of the ether gives 93 parts of a viscous dark-brown oil containing 31.2% sulfur, as compared to the theoretical value of 31.4% sulfur for $C_{15}H_{30}S_3$.

Twenty-eight parts of the sulfurized pentadecene is dissolved in 50 parts of dry toluene and charged with 3 parts of cobalt polysulfide catalyst prepared according to the procedure described in co-pending application of F. K. Sigalgo, Serial No. 319,241, filed February 16, 1940, into a steel reaction vessel equipped with an efficient device for agitation and adapted for operation at high temperatures and pressures. Hydrogen under pressure is admitted to the reac-

tion vessel until the total pressure is between 2000 and 2500 lbs. per square inch. The mixture is then heated at 150° to 160° C. for about 4 hours. After cooling, the reaction vessel is purged to remove hydrogen sulfide which forms in the reaction, and the liquid is filtered to separate the catalyst. Fractional distillation of the catalyst-free oil gives 3.8 parts of unreacted pentadecene-7 suitable for reuse in the first step of the process, 10.2 parts of pentadecanemonothiol, B. P. 173°-174° C./16 mm., 5.4 parts of pentadecanedithiol, B. P. 196-197° C./16 mm. and 3.6 parts of high boiling residue. The monothiol fraction is presumably a mixture of pentadecane-7-thiol and pentadecane-8-thiol.

Thirty parts of the pentadecanethiol is added slowly during one hour to 54 parts of 70% nitric acid in a corrosion resistant reaction vessel fitted with a reflux condenser and an efficient agitating device. Heating at 80° C. is continued for about 4 to 5 hours in order to remove excess nitric acid. The mixture is then diluted with 100 parts of water and exactly neutralized by adding 32 parts of 30% caustic soda solution. Evaporation of the neutral solution gives a thick paste which is extracted with ethanol to separate the pentadecane sodium sulfonate from insoluble inorganic salts. After filtering the latter, the alcohol solution is again evaporated. On repeating this treatment once or twice, there is obtained 37.5 parts of soft brown solid containing 8.5% of sulfur, as compared to the theoretical value of 10.2% for pentadecane sodium sulfonate. This product is found to possess powerful sudsing action, good detergent properties, and high efficiency as a wetting agent by the test of Draves and Clarkson (Am. Dyestuffs Reporter, 20, 201 (1931)).

Example II

Two hundred ten parts of pentadecene-7 is sulfurized by treating with 64 parts of powdered sulfur at a temperature of 150-160° for a period of about 6 hours. The resulting product is taken up in an equal volume of dry ether, filtered after standing to remove a small amount of unreacted sulfur, and the ether solution evaporated on the steam bath to obtain a viscous dark-brown oil having a faint odor characteristic of aliphatic sulfur compounds.

One hundred fifty parts of the sulfurized olefin is hydrogenated in the presence of 12 to 15 parts of precipitated cobalt polysulfide catalyst prepared as described in the copending application of F. K. Signaigo, Serial No. 319,241, filed February 16, 1940, at 160° C. and pressure of 2000 lbs. per square inch. The pressure drop during 2.75 hours is 800 lbs., and on cooling the reaction vessel, the product is removed, filtered to separate the catalyst, and fractionally distilled to yield 24.5 parts of unreacted pentadecene-7, 52.9 parts of pentadecanemonothiol, 24.3 parts of pentadecane-7, 8-dithiol, and 16.4 parts of residue. The monothiol is oxidized to pentadecane sulfonic acid according to the procedure of Example I, and the dithiol is treated as follows:

A solution of sodium hypochlorite is prepared by passing 51.4 parts of chlorine into 225 parts of water containing 63 parts of sodium hydroxide and added slowly to a stirred suspension of 30.6 parts of pentadecane-7,8-dithiol in a solution of 32.5 parts of sodium carbonate and 360 parts of water. The reaction mixture is heated to 75° to 80° C. until substantially all of the oil layer

disappears. The resulting homogeneous solution is saturated with sodium chloride and evaporated on the steam bath. The product is extracted with boiling alcohol, filtered to remove inorganic salts, and the solution evaporated. There is obtained about 38 parts of a brown, brittle solid, which consists of the disodium salt of pentadecane-7,8-disulfonic acid. On dissolving the disodium salt in water, persistently foaming solutions are obtained.

Although in the foregoing examples, certain definite conditions of temperature, pressure, reaction times, and the like have been referred to, it is to be understood that these values are subject to considerable variation within the scope of the invention without departing from the spirit thereof.

Broadly speaking, the solubilization of olefin hydrocarbons according to this invention comprises three closely interdependent integrated steps. In the initial step, olefins of suitable structure and molecular weight are converted to the corresponding sulfurized derivatives by direct interaction with sulfur at temperatures between about 100° C. and about 200° C. and preferably at about 125° C. to 200° C. The reaction can be carried out either at atmospheric or under super-atmospheric pressure, depending on the properties of the starting olefin, using at least one and preferably about three atomic proportions of sulfur per mole of olefin. The length of time required will be governed by the temperature and to some extent by the structure of the olefin. As pointed out in the examples, one hour at reaction temperature is usually sufficient to bring about complete dissolution of sulfur and the mixture is preferably heated for an additional 5 to 7 hours or more to insure completeness of reaction. The sulfurized products consist of viscous dark-brown oils containing from one to three atoms of sulfur depending on the actual proportions of reactants. These materials can be partly purified prior to hydrogenation according to the general method disclosed in Example I or can be employed without further treatment.

In the hydrogenation of sulfurized olefins in accordance with this invention, the crude or partly purified products are treated with hydrogen under a pressure of at least 10 atmospheres and preferably between 100 and 300 atmospheres at a temperature above 100° C. but below 300° C. in the presence of 5 to 15 parts of a sulfactive hydrogenation catalyst. In general, temperatures of 125° C. to 200° C. are sufficient to bring about a smooth and complete hydrogenation during a period of about 2 to 4 hours. Similarly, although the upper pressure limits of the hydrogenation process will be determined only by the practical limitations of the reaction vessel, pressures much above 1000 atmospheres will seldom be necessary.

In the practice of this invention, sulfides of the hydrogenating metals of groups I, VI and VIII of the periodic table are employed as catalysts. Typical examples of catalysts coming within this classification are cobalt polysulfide, cobalt monosulfide, nickel sulfide, iron sulfide, molybdenum trisulfide, and copper sulfide. The catalysts are suitably prepared by precipitation from a solution of a soluble salt of the hydrogenating metal with alkali metal or ammonium sulfides as described in the copending application of F. K. Signaigo, Serial No. 319,241, filed February 16, 1940; alkali metal sulfide activation of an alloy of the hydrogenating metal with aluminum

as described in the copending application of B. W. Hawk, Serial No. 353,936, filed August 23, 1940; or by treating a pyrophoric hydrogenation catalyst with hydrogen sulfide or sulfur as described in the copending application of F. K. Signaigo, Serial No. 319,242, filed February 16, 1940. In some cases it may be feasible to carry out the latter method in situ. For batchwise liquid phase hydrogenation, the catalysts of this invention are conveniently employed in finely divided form either as dry powders or suspended in benzene or toluene. For continuous liquid phase hydrogenation, catalyst lumps or briquettes of suitable size are preferred. As mentioned in the above examples, cobalt polysulfide catalyst is particularly suited for the hydrogenation of sulfurized olefins to thiols.

On hydrogenation, as described above, sulfurized olefins are converted to a mixture of the corresponding mono- and dithiols in the molecular ratio of about two to one. Other products are small amounts of unreacted and regenerated olefin and high boiling residues. These materials can, if desired, be separated by fractional distillation, or the crude product can be employed for oxidation without extensive purification. Generally speaking, it is desirable to top the product in order to remove unreacted olefin for recycle in the process.

Oxidation of the mono- and dithiols of this invention to sulfonic acids is conveniently carried out by treating under mild conditions with suitable reagents such as nitric acid and sodium hypochlorite solutions. In general, nitric acid (70%) is the preferred oxidizing agent for mono-thiols, whereas hypochlorites are more satisfactory for treating dithiols which may undergo further degradation under more drastic conditions. In either case, the pure thiols or the crude hydrogenation product is treated with the oxidizing reagent at moderate temperatures of the order of 60° to 100° C. The length of time and number of treatments required will be governed largely by the ease with which the thiols are converted to soluble sulfonic acids. In some cases, particularly where the oxidation proceeds vigorously, it may be desirable to dilute the thiols with inert solvents such as carbon tetrachloride, tetrachloroethane and the like. In other instances, oxidizing reagents such as chromic acid, hydrogen peroxide, permanganic acid, or air in the presence of catalysts will be found satisfactory for this transformation. Methods for isolating the products will be found in the examples. A particularly important feature of the invention is that the integral steps of the process as described above can be carried out successively in suitable corrosion-resisting high pressure equipment without transfer or loss of material.

In the practice of the invention, there can be employed as raw materials monoolefin hydrocarbons containing at least six and preferably eight or more carbon atoms having at least one hydrogen atom attached to each carbon atom of the ethylenic bond. Olefins of this general class can be obtained by dehydration of the corresponding alcohols, decarboxylation of unsaturated acids, dehydrogenation of saturated hydrocarbons, decarbonylation of unsaturated alcohols, polymerization of lower olefins such as ethylene and propylene, dehydrohalogenation of halogenated paraffin hydrocarbons or from appropriate petroleum cracked distillate fractions. Other sources of materials will be readily apparent to those skilled in the art. Typical olefins of this

group are hexene-3, octene-2, methyl-2-decene-4, pentadecene-7, hexadecene-1, heptadecene-8, octadecene-2, triacontene-14, pentatriacontene-17, methyl-4-dodecene-4, dimethyl-7,8 pentadecene-7, and hexyl-2-decene-1. These and similar olefins, either alone or in admixture, are smoothly and conveniently converted to surface-active sulfonic acids according to this invention.

Aliphatic sulfonic acids coming within the scope of this invention are characterized by a remarkable stability and by outstanding properties as textile reagents or finishing agents. The utility of specific sulfonic acid compositions as wetting agents, detergents, scouring agents, sudsing agents, cotton softeners, and the like will, of course, be governed by considerations of solubility in water, structure and molecular weight. For some uses, it may be desirable to employ the free sulfonic acids, but for the most part, it is preferable to use salts of metals such as sodium, potassium, calcium, and magnesium, or salts of amines such as long-chain primary amines, ethanolamine, glucamine, aniline, pyridine, piperidine, and the like.

It is apparent that many widely different embodiments of this invention may be made without departing from the spirit and scope thereof, and therefore, it is not intended to be limited except as indicated in the appended claims.

We claim:

1. The process which comprises bringing a monoolefin hydrocarbon containing at least 6 carbon atoms into admixture with at least one atom of sulfur per molecule of hydrocarbon, heating the mixture at a temperature between 100° and 200° C. for at least one hour, catalytically hydrogenating the resulting product at a temperature between 100° and 300° C. under a pressure of at least 10 atmospheres until the reaction is complete, cooling the resulting product, and oxidizing to a sulfonic acid.

2. The process which comprises bringing a monoolefin hydrocarbon containing at least 8 carbon atoms into contact with sulfur present in an amount of at least 3 atoms of sulfur per molecule of hydrocarbon at a temperature of about 125° to about 200° C. for at least one hour, catalytically hydrogenating the resulting mixture in the liquid phase at a temperature of about 125° to about 200° C. and under a pressure of about 100 to 300 atmospheres in the presence of a sulfactive hydrogenation catalyst, cooling the resulting hydrogenated products and bringing same in contact with a 70% nitric acid solution at a temperature between 60° and 100° C., thereby producing sulfonic acids.

3. The process in accordance with claim 1 characterized in that the catalytic hydrogenation reaction is carried out in the presence of a base metal sulfide hydrogenation catalyst.

4. The process in accordance with claim 1 characterized in that the catalytic hydrogenation reaction is carried out in the presence of a ferrous group metal sulfide hydrogenation catalyst.

5. The process in accordance with claim 1 characterized in that the catalytic hydrogenation reaction is carried out in the presence of a cobalt polysulfide hydrogenation catalyst.

6. The process in accordance with claim 1 characterized in that the catalytic hydrogenation reaction is carried out in the presence of a molybdenum sulfide hydrogenation catalyst.

ALFONSO M. ALVARADO.
